Attorney

UNITED STATES PATENT OFFICE.

LOUIS L. BORNHOLDT, OF HIGHMORE, SOUTH DAKOTA.

PUMP.

Application filed June 22, 1923. Serial No. 646,992.

To all whom it may concern:

Be it known that LOUIS L. BORNHOLDT, a citizen of the United States, residing at Highmore, in the county of Hyde and State 5 of South Dakota, has invented certain new and useful Improvements in Pumps, of which the following is a specification.

This invention relates to certain new and useful improvements in pumps, and has particular reference to air pumps of the solid 10 piston rectilinear type.

The primary object of the invention is to construct a pump of the above type wherein in the air intake is of a novel form and is 15 provided with a shut-off valve for rendering the check-valve thereof inoperative so that the device may be effectively employed for testing compression in cylinders of gasoline engines or the like.

Another object of the invention is to embody the above features in a pump in such 20 manner as to render the construction extremely efficient, simple and durable.

With the above general objects in view, 25 and others that will become apparent as the nature of the invention is better understood, the same consists in the novel form, combination and arrangement of parts hereinafter more fully described, shown in the accompanying drawing, and claimed.

In the drawings, wherein like reference 30 characters indicate corresponding parts in the two views,

Figure 1 shows a pump constructed in 35 accordance with the present invention, partly in elevation, partly in vertical section, and partly broken away, and

Figure 2 is a top plan view of the device 40 shown in Fig. 1 with parts removed.

Referring more in detail to the drawing, 45 the invention embodies a base 5 of elongated form, and preferably consisting in a heavy casting as is usual with pumps of this character. As shown in Fig. 1, the base 5 is provided with a longitudinal passage 6 having upwardly extending flanged ports 7, 8 and 9 which open through the upper end of the base and spaced apart and in alignment with each other longitudinally as indicated 50 in the figures. The base 5 is provided with an upstanding internally threaded socket 10 at one end of the same with which the port or opening 9 is concentric, and the lower end of a pump barrel 11 is threaded into this socket as shown in Fig. 1. A piston head 12 is vertically reciprocable in the

cylinder 11 and is attached to the piston rod 13 which extends upwardly through a cap 14 suitably provided on the upper end of the barrel 11. The piston 12 is preferably of the construction shown embodying oppositely positioned cup-shaped lever members provided with filler blocks and clamped tightly together upon the threaded lower end portion of the piston rod 13 by means of nuts 15. Any suitable means may be provided for the convenience of reciprocation of the piston rod 13.

The base 5 is provided with a relatively small internally threaded socket 16 eccentric 70 with and surrounding the intermediate port 8, and the lower end of a tube 17 is threaded into this socket 16 as shown in Fig. 1, the upper end of the tube 17 being provided with any suitable form of check valve 18 75 which is spring pressed at 19 to normally close and open in the cap 20 provided in the upper end of the tube 17. The manner of use and purpose of this check valve is well known in the art, the valve 18 being unseated by sections upon the upstroke of the piston 12 for allowing air to be readily drawn through the tube 17, port 8, passage 6 and port 9 into the lower end of the pump valve 11. The check valve 18 automatically seating 80 upon the downstroke of the piston 12 for causing the air to be forced through the outlet port 7. In order to render the check valve 18 inoperative so as to prevent air from being drawn into the cylinder 11, a 85 cutoff valve 21 is placed in the tube 17 between the check valve 18 and the port 8. This cutoff is preferably in the nature of a hand clutch adapted for manual operation by means of a handle 22, although any desired form of cutoff valve may be provided.

The wall of the port 7 is threaded for reception of the nipple 23 which is provided in the usual manner upon one end of the outlet hose 24, a portion of which is shown in 100 Fig. 1. It will be noted that while a small check valve 18 has been shown, any equivalent form of check valve may be employed within the spirit of the invention.

The usual pivoted foot piece 25 may be 105 carried by the base 5 for use in fitting the pump when the same is in use.

From the foregoing it will be seen that when the device is employed as a compression pump for inflation of tires or like uses, 110 the cutoff valve 21 will be opened and the device operated in the usual manner. How-

ever, when testing the compression of the cylinder of internal combustion engines or similar uses, the cutoff valve 22 is closed so that no air can be drawn through the 5 tubes 7.

Minor changes may be made without departing from the spirit and scope of the invention as claimed.

What I claim as new is:—

- 10 1. In an air pump of the solid piston rectilinear type, a base, said base having a passage provided with three upwardly extending ports, a pump barrel attached to the base in surrounding relation to one of said ports, 15 an air intake tube attached to the base and surrounding an intermediate one of said ports, a check valve carried by said tube, a cutoff valve carried by the tube between

the check valve and the intermediate port of the base, and an outlet hose connected with 20 the remaining port of the base.

2. In a pump of the class described, a base having a passage provided with three ports, a pump barrel attached to the base in surrounding relation to one of said ports, a 25 check valve in operative relation to another of said ports for permitting the passage of air to the passage upon the section stroke of the piston of said barrel, means associated with the last named port between the passage and the check valve for cutting off communication of said port with the atmosphere and an outlet hose oppositely associated with the remaining port of the base.

In testimony whereof I affix my signature.
LOUIS L. BORNHOLDT.
